OPERATING LEVER FOR CLOSING DROP
DOORS ON RAILWAY HOPPER CARS

Stanley Radis, West Homestead, Pa.

Application October 18, 1944, Serial No. 559,284

1 Claim. (Cl. 105—306)

1

This invention relates to operating levers for closing drop doors on railway hopper cars and has for its principal object the provision of such a lever which may be positively engaged with the car hopper and the door when in operating position so as to avoid any danger of the lever slipping when closing the doors.

Heretofore it has been the practice to manually move the hopper doors until they engage a preliminary latch, then to utilize an ordinary pinch bar to try to force the door into a completely closed position where it is engaged by a permanent locking latch. The use of such pinch bars of standard design was objectionable and dangerous since they provided no means for preventing the bar slipping when force was applied to close the door and bars slipping from engagement with the doors have caused numerous and serious injuries to workmen.

The present bar, due to the fact that it has a positive engagement with the car hopper and with the door, cannot slip during the door closing operation and the danger of injuring the operator or fellow-workmen has been entirely eliminated.

In the drawings:

Figure 1 is a fragmentary side elevation of a car hopper showing door of hopper open with operating lever anchored to hopper;

Figure 2 is a similar view showing door closed by operating lever;

Figure 3 is a side elevation of operating lever;

Figure 4 is a plan view of the lever of Figure 3;

Figure 5 is an elevational view of the lever with the anchor omitted; and,

Figures 6 and 7 are side and face views respectively of the anchor or hook of the operating lever.

The device of this invention is of simple construction and consists of only three parts, namely, a lever bar designated generally by the letter A, a locking hook or link designated generally by the letter B, and a fulcrum bolt designated generally by the letter C.

The lever bar A is composed of one piece of steel, suitably shaped, and has formed intermediate its ends and projecting from one edge thereof a fulcrum portion or lug 2 having a bolt-receiving opening 3. The fulcrum portion 2 is positioned nearer one end of the bar than the other and the longest portion of the bar, which is designated by the numeral 4, has a constantly reduced cross-section so as to have a size suitable for convenient gripping by the operator. That portion of the bar opposite the portion 4 is desig-

nated by the numeral 4' and is relatively short as compared with the length of the portion of the bar 4. The portion 4' of the bar is constantly reduced in cross-section from said bearing portion 2 to its terminal end and is so shaped that it has a slow curve shape in the direction of its longitudinal axis, such curve being of sufficient magnitude to provide clearance for any projecting parts of the car door. The terminal end of the part 4' is of such reduced cross-section that it can be readily inserted in an opening or socket 5 formed in an extension member 6 on the angle 6 on the car door 7.

The link hook B is provided with a clevis end 8 adapted to be fitted over the fulcrum portion 2 and to be fulcrumed on the bolt C, which projects through aligned openings in the clevis end 8 of the hook B and the opening 3 in the fulcrum portion 2 of the lever bar. The terminal or free end of the hook member B is bent back upon itself to form a substantially U-shaped terminal hook portion 9 which, when the bar is in operative position, is engaged in an aperture 12 formed in an extension 13 of the door latch mechanism 14.

In the operation of closing the hopper door 7, the reduced end of the short portion 4' of the lever bar is inserted in the opening or socket 5 in the reinforcing angle 6 of the door and the hook portion 9 is engaged in the aperture 12 in the extension 13 of the latch mechanism 14 whereby the bar is anchored by the hook to the rigid structure of the hopper and the end of the bar is anchored in the socket 5 of the door, so that when force is applied to the end of the portion 4 of the bar, the bar will fulcrum around the bolt C and force the door inwardly into closed position. By anchoring the bar with the hook member B, there is no danger of the bar flying loose from the door and injuring either the operator or fellow-workmen.

Having thus described my invention, what I claim is:

In combination with a railway hopper car, a pivot member on said car, a door hanging from said pivot member, means on the lower part of said door extending outwardly therefrom and having an opening therein, a portion on said car extending toward said door above the last said means and having an opening therein, a lever bar having a fulcrum portion thereon, the portion of said lever bar extending upwardly from said fulcrum portion being materially longer than the portion of said lever bar extending downwardly from said fulcrum portion, said longer portion of said lever bar having its terminal end shaped to

permit gripping by the operator, the lower end of the lever bar being shaped to permit ready insertion into the first of said openings, a link hook pivotally mounted on said bar at the fulcrum portion, said hook having its free end bent back to form a substantially U-shaped hook terminal to be engaged with the second of said openings so as to form an anchor for said lever bar and permit said lever bar to move about the pivot connection between said hook and lever bar when force is applied to said longer portion of said lever bar and thereby force said relatively short portion of said lever bar to move the car door into closed position.
